ATTORNEY.

UNITED STATES PATENT OFFICE.

CARL T. SWENSON, OF MILWAUKEE, WISCONSIN.

TRACE CONNECTER.

Application filed January 31, 1927. Serial No. 164,798.

The invention relates to trace connectors for harnesses.

The object of the invention is to provide a trace connector of strong and durable construction wherein the connection between the parts of the connector with the hame and the trace are made by bolts and that part of the connector associated with the trace may swing in the plane of its connection with the part of the connector associated with the hame but is prevented from swinging laterally relative thereto, thus decreasing wear of the parts.

The invention further consists in the several features hereinafter set forth and more particularly defined by claims at the conclusion hereof.

In the drawings Fig. 1 is a view of a connector embodying the invention in applied position on a horse;

Fig. 2 is a side elevation view of a connector embodying the invention, parts of the trace being broken away and parts being shown in section;

Fig. 3 is a plan view of the connector;

Fig. 4 is a detail sectional view taken on the line 4-4 of Fig. 2.

In the drawings the numeral 5 designates the hame, 6 the bolt-attaching lugs secured thereto, 7 the hame bolt, 8 the hame part of the connector, 9 the trace part of the connector, 10 the trace bolt and 11 the trace.

The hame part 8 includes a tubular portion 12 through which the bolt 7 passes and upon which it is pivotally mounted for lateral swinging movement, the lower end 13 of the bolt having threaded engagement with the lower lug 6. The part 8 also has a ring portion 14, preferably formed integral with the tubular portion and extending from the end portions thereof.

The trace part 9 has end portions 15 apertured to receive the trace bolt 10, the lower one of said end portions being threaded to receive the lower threaded end 16 of the bolt, and has a channel portion 17 to engage the ring portion 14. The sides 18 of this channel are relatively wide and long so that a deep channel is formed which engages the inner and side parts of the ring over a considerable portion of its area, the length of engagement being greater than the radius of the ring and, as shown, about two-thirds of its diameter, with the result that while

the base portion of this channel section is curved so that the clevis may turn in the plane of its connection with the ring portion 14, it cannot swing laterally relative thereto, with the result that the wear on the parts is greatly diminished over prior constructions and the lateral swinging is taken care of at either of the pivotal connections provided by the bolts 7 and 10. Thus the wide sides 18 act as stops to prevent lateral swing of the part 9 relative to the ring 14.

The bolt 10 is pivotally mounted in a metal sleeve 19 and firmly held between the folded wide safe portions 20 of the trace which, together with the folded front end 70 21 of the trace proper, are secured together by double lines of stitching 22 and 23 which take the strain of the pull and are further secured by a rivet 24 close to the sleeve 19.

With this construction the bolts 7 and 10 75 permit lateral movement of the trace relative to the hame and the connection between the ring portion 14 and the part 9 permits vertical swinging movement of the trace and because of the large bearing area and the 80 reduction in wear previously pointed out the possibility of breakage through wear at this important point of the harness is reduced to a minimum.

I desire it to be understood that this invention is not to be limited to any particular form or arrangement of parts except insofar as such limitations are specified in the claim.

What I claim as my invention is:

In a trace connector, the combination of a member having a hame-bolt-receiving sleeve portion and a ring portion, a member having a central ring-engaging channel portion movable relative to said ring in the plane of its connection and provided with integral sides engaging the sides of the ring for a distance greater than the radius of said ring portion to form stops preventing lateral swinging movement, said member having integral arm portions projecting laterally from opposite sides of said channel portion whereby openings are provided for the direct insertion of said channel portion within said ring portion, said arms having 100 trace-bolt-receiving openings in their ends.

In testimony whereof, I affix my signature.
CARL T. SWENSON.
